STOP AND TURN SIGNAL

Fusajiro Mamiya, Los Angeles, Calif.

Application April 28, 1933, Serial No. 668,323

2 Claims. (Cl. 116—39)

This invention relates to improvements in vehicle carried signals for indicating the contemplated turns and stops, and more particularly resides in the provision of an efficient fluid operated actuator for such signals.

One of the objects of the invention is to provide a signal such as described which will be subject to ready installation on automobiles of various makes as well as simple, compact, inexpensive, effective at night as well as in day time, and capable of easy and accurate operation without tending to distract the driver.

Another and important object is the provision of a fluid operated actuator which is comprised of comparatively few simply constructed parts in a decidedly compact arrangement making for inexpensiveness of construction, ease of installation, and reliability of performance in the signal as a whole.

A further object is to provide a signal such as described, that is subject to operation by making a simple connection of the actuator to the intake manifold of the vehicle engine.

Yet another object is to provide in a signal of the character described, a combined electric switch and fluid control valve which is of simple compact and inexpensive form as well as reliable in operation to control the movements and illumination and also indicate the positions of the signaling member.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to the drawings:

Fig. 1 is a fragmentary perspective view of an automobile equipped with the signal of this invention;

Fig. 2 is a vertical sectional view taken on the plane of line 2—2 of Fig. 1;

Fig. 3 is a vertical section taken on the plane of line 3—3 of Fig. 2;

Fig. 4 is a vertical section taken on the plane of line 4—4 of Fig. 3;

Fig. 5 is an enlarged top plan view of the control valve;

Fig. 6 is a cross section taken on the plane of line 6—6 of Fig. 5;

Fig. 7 is a horizontal sectional view taken on the plane of line 7—7 of Fig. 6;

Fig. 8 is a horizontal sectional view taken on the plane of line 8—8 of Fig. 6;

Fig. 9 is a schematic view of the vacuum operated actuator.

As shown in the accompanying drawings, one embodiment of the invention comprises a casing 10 secured by an adjustable bracket 11 to a side of an automobile as shown at A. Arranged to swing from concealed position within the casing to its various signal positions and vice versa is a semaphore signaling arm 12 capable of simulating the standard stop and turn signals, as shown in Fig. 1. This arm is hollow and has suitably colored sides 13 of glass or the like, illuminated by an electric light 14 contained in the arm whereby the signals may be effectively displayed at night.

A pivotal mounting for the arm 12 is made by forming annular bearing flanges 14' at the margins of openings 15 in the opposed faces of the casing 10 and extending the flanges into a tubular portion 16 of the arm as shown in Fig. 2. Covering said openings 15 are lenses either plain or colored and which are illuminated by the light arranged to be in part opposite said lenses. By this illuminating arrangement the effective display of the various signals, particularly at night, is assured.

It should be noted that the signal arm 12 has an arcuate extension 17 which is overlapped by the upper curved portion 18 of the casing 10 at all times whereby to form a weatherproof top for said casing and protect the working parts 35 interiorly thereof.

The fluid actuator 20 is mounted in the casing 10 and comprises what may be termed a simple vacuum or fluid engine, characterized by a closed cylinder 21 in which a piston 22 is mounted for reciprocal movement. Extending from the piston out through a stuffing box 23 is a piston rod 24 formed in part as at 25 to serve as a rack bar. This rack bar portion 25 is engaged with a gear segment 26 formed or otherwise provided on or as a part of the tubular end portion 16 of the signal arm. This arrangement, as seen with reference to Figs. 2 and 3, provides for swinging the signal arm into and out of its operative positions upon appropriate movement of the piston 22. In the present instance the piston is arranged to be actuated by creating in the cylinder 21 a differential in fluid pressures, said cylinder being communicated as will be hereinafter disclosed with the atmosphere and with the intake manifold 55

(not shown) of the automobile internal combustion engine.

Selective movement of the piston to various extents necessary to selectively variously move the signal arm into and out of its signal positions is made possible through the employment of a novel porting of the cylinder and an especially constructed manually operable control valve.

As here shown the cylinder has four ports 27, 10 28, 29 and 30 substantially equidistantly spaced therein, each port being closed by the piston when the latter is opposite it, whereby the piston acts also as a valve. Leading from these ports are four conduits or passages 31 formed as separate 15 passages in a solid pipe like member 32 which is connected by suitable fittings 33 to the casing 10. The member 32 is joined to a combined control valve and switch 34 which is preferably mounted on the steering column B as shown in 20 Fig. 1. Extending from the valve 34 to the intake manifold of the vehicle engine (not shown) is a pipe line 35 whereby the suction action of the engine is effective through the pipe line 35 and passages 31 to permit of operation of the 25 piston 22 in the cylinder 21, said action being under control of the valve 34.

The valve 34 comprises a casing 37 having a stationary valve plate 38 arranged as a horizontal partition therein. Arranged in an arcuate row in the plate 38 are openings 40, 41, 42 and 43 which are connected by short tubes 44 with the passages 31. A rotatable valve plate 45 is mounted on the plate 38 being guided by a pin 46 which is engaged in a slot 47 in the plate 38. A leaf spring 48 is fixed at one end to the rotatable plate 45 and at its other end carries a pin 49 arranged to frictionally engage the under side of the top wall 50 of the casing. The spring forces the plate 45 into close engagement with the stationary plate 38. Depressions 51 are provided in said top wall to receive the pin when the valve is in its operative positions whereby to releasably hold the valve in the desired positions. A rotatable yoke 52 embraces the spring 48 and has a pintle 53 which is extended out through the top wall 50. Fixed on the pintle 53 is an operating handle 54 which when turned rotates the valve plate 45 through the drive connection consisting of the yoke 52 and spring 48.

50 In the center of the stationary plate 38 is an opening 55 which registers with the suction pipe line 35 and with one end of a groove 56 formed in the under side of the rotatable valve plate 45. This groove extends radially whereby its outer end is disposed to register with the openings 40, 41, 42 and 43 upon appropriate turning of the plate 45.

Within the valve casing is a normally closed switch 57 controlling the light 14 in the signal arm. The contacts 58 and 59 of the switch are engaged at all times except when the signal is in an inoperative position at which time the pin 46 (see Fig. 8) engages and holds contact 59 out of engagement with contact 58. Thus it is seen that upon moving the valve to operate the signal the switch 57 is closed whereby to light the light 14 in the signal arm.

As a means for communicating the cylinder 21 with the atmosphere the valve plate 45 has small openings 61 and 62 disposed so as to register with the openings 40, 41, 42 and 43. The valve casing is open to the atmosphere through a vent 63. It is now seen that when the openings 61 and 62 are in registration with certain of the openings 40, 41, 42 and 43 and the latter are communicated

through the passages 31 to the cylinder 21, said cylinder will be open to the atmosphere, and permit the higher pressure atmosphere to operate the piston 22 as will be more fully hereinafter explained.

Operation

Assuming that the signal arm is in concealed position in the casing 10, the operating handle 54 is in a position corresponding to the signal arm. To now make a stop signal, the operator moves the handle 54 to the left until it assumes approximately the position the signal arm will take in making a stop indication.

On this movement of the handle the valve disc 45 is turned to bring the groove 56 into registration with the opening 41 in the plate 38. This establishes communication of the cylinder 21 with the intake manifold of the engine (not shown) through pipe line 35, opening 55, groove 56, opening 41, passage 31, and cylinder port 28, and thereby creates a sub-atmospheric pressure in said cylinder below the piston 22, which latter is at the top of the cylinder. When the valve is in the position just described whereby to effect the stop signal, the vent opening 61 is in registration with the valve opening 40 which it is noted controls the cylinder port 27 at the top of the cylinder. Thus it is seen that the atmosphere will enter the cylinder through the port 27 above the piston and this higher pressure fluid becomes effective to move the piston downward until the piston covers the port 28, at which time the piston movement ceases due to the fact that the means for creating sub-atmospheric pressure is removed and the pressure below the piston reaches that of the atmosphere. The restoration of atmospheric pressure beneath the piston when the latter closes port 28 is provided through port 29, passage 31 leading from said port valve opening 42 and vent opening 62 which is then in registration with said opening.

Upon this downward movement of piston 22 the piston rod rack bar operates through the gear segment on the signal arm to move the signal arm into the "stop" position shown in full lines in Fig. 1. It should be noted that the piston and signal parts will maintain through friction the positions to which they are moved. The switch 57 closes upon movement of the valve to a signalling position and remains closed until the signal is moved back into non-signalling position, and the light 14 therefore effectively displays the signal as hereinbefore noted.

To restore the signal to non-signalling position the operator moves the handle 54 to the right to position perpendicular with the longitudinal axis of the automobile and the valve plate 45 is moved to bring the groove 56 into registration with valve opening 40. This creates a sub-atmospheric pressure through the cylinder port 27, the passage 31 leading from said port, valve opening 40, groove 56 opening 55 and pipe line 35 leading to intake manifold. As soon as the pressure becomes sub-atmospheric above the piston 22 the atmospheric pressure beneath the piston moves the piston upwardly and thereby restores the signal arm to concealed position. When the piston is thus moved it covers port 27 and thereby destroys the negative pressure.

It should be noted that at times during operation of the valve certain portions of the cylinder are vented to the atmosphere through vent ports 61 and 62 at the same time a sub-atmospheric pressure is being created in said cylinder

portions. The creation of sub-atmospheric pressures is made possible under these conditions since the vent openings are comparatively small and but a slight pressure differential is necessary to effect movement of the piston. In other words the "leaks" resulting from the vents 61 and 62 are so small as to be negligible as against an evacuation of air from the cylinder sufficient to create a sub-atmospheric pressure therein.

10 It is now seen that the valve may be selectively operated to bring the groove 56 into registration with any of the openings 40, 41, 42, and 43 and to thereby cause the desired signal. When the valve is moved to bring the opening 42 into play the negative pressure is effective through the cylinder port 29 and the piston moves sufficient to bring the signal arm to the horizontal left turn position. When the valve opening 43 is brought into registration with groove 56, then the sub-pressure is created through port 30 and the piston moves sufficient to bring the signal arm to the right turn position.

15 It should be noted that the piston operates in the same manner as described in connection with the right turn signal and that the signal arm may be brought back into concealed position by simply turning the valve to bring the opening 40 and port 27 into play as described hereinbefore.

20 It should be noted that the combined switch and control valve operates to simultaneously control the electric light and the operation of the vacuum actuator in a most efficient manner. Also the handle of the control valve in assuming

positions corresponding to the signal arm serves as a "tell-tale" indicator for the benefit of the operator.

25 It is now apparent that the apparatus hereof provides for the advantages and objects of this invention in a particularly efficacious manner.

I claim:

1. In a signal, a casing, a signal member mounted to swing into and out of the casing, a gear segment on said member, a cylinder immovably mounted in said casing below said segment and against which said signal member rests when in non-signaling position, a piston reciprocally mounted in said cylinder, a rack bar connected directly with said piston and extended upwardly out of said cylinder and meshing with said segment, and means for creating variational fluid pressures in said cylinder.

2. In a signal, a casing, a signal member pivoted at one end within the upper end of said casing and arranged to swing into out of concealed position within said casing, a gear segment carried by said member, a cylinder fixed immovably to the rear wall of said casing below the plane of the pivotal mounting of said member and disposed to act as a stop for the member when the latter is in concealed position, a piston in said cylinder, a rod fixed to said piston, a stuffing box out through which said rod extends, and rack teeth on said rod meshed with said gear segment.

FUSAJIRO MAMIYA.
